UNITED STATES PATENT OFFICE.

JOHN J. BERRIGAN, OF CHICAGO, ILLINOIS, ASSIGNOR OF ONE-THIRD TO JOHN B. BERRIGAN AND ONE-THIRD TO KATHERYNE P. MALON, BOTH OF CHICAGO, ILLINOIS.

HYDRAULIC PRESS.

Application filed November 12, 1923. Serial No. 674,123.

To all whom it may concern:

Be it known that I, JOHN J. BERRIGAN, a citizen of the United States, residing at Chicago, in the county of Cook and State 5 of Illinois, have invented a certain new and useful Improvement in Hydraulic Presses, of which the following is a specification.

This invention relates to a hydraulic press, and particularly to a horizontal hydraulic 10 press. It has for one object to provide a satisfactory hydraulic press which operates in a horizontal position. Another object is to provide a press which while having a comparatively short initial travel, limited 15 by the length of the compression cylinder, will be able to compress through a distance longer than the length of the cylinder. Other objects will appear from time to time throughout the specification and 20 claims.

My invention is illustrated more or less diagrammatically in the accompanying drawings, wherein—

Figure 1 is a side elevation showing the 25 press partly open at top and bottom;

Figure 2 is a vertical cross section showing the press entirely open;

Figure 3 shows the press partially compressed;

Figure 4 shows the entire compression assembly moved laterally for a second compression stroke;

Figure 5 is a vertical cross section on the line 5—5 of Figure 4;

Figure 6 is a vertical section on an enlarged scale showing a portion of one of the bottom plates of the press;

Figure 7 is an elevation with parts broken away showing one of the partitions within 40 the press;

Figure 8 is a horizontal cross section taken on the line 8—8 of Figure 7;

Figure 9 is a section on an enlarged scale taken on the line 9—9 of Figure 3;

Figure 10 is a section on an enlarged scale showing one of the attaching members by means of which the top and bottom plates are held in position;

Figure 11 is a modified view similar to 50 Figure 9;

Figure 12 is a side elevation showing the pipe of Figure 11.

Like parts are designated by like characters throughout.

A is a foundation of floor upon which the 55 press is positioned, B, B¹ are end supports joined by side channel members C C which serve as runners for the partitions, bind the two end frame members together, and carry the outside frame of the outside casting. D is a hydraulic compression cylinder within which a plunger is mounted. D¹, D² are pipes by means of which pressure may be applied to either side of the plunger so as to move it to the right or left. 60

E is a platen adapted to slide on the members C, C and against which the pressure is exerted. F, is a second platen at the opposite end of the press which is directly connected to the plunger rod F¹. 65

Mounted in the platen F are two rods G, G. These rods are adapted to slide through the perforations in the platen E and the perforations in the end frame members B. 70

H, H are partitions mounted within the press, notched as at O³, perforated to permit the rods G to slide through them, and flexibly joined together by means of chains H², H². 75

The platens and the partitions are normally of such size and shape as to contact the bottom of the floor plates L, below described.

I is a side casing about the sides of the 80 press. As here shown it is a hollow casing, Within it are mounted steam heating pipes I¹, I¹. This feature may be omitted where it is not necessary to heat the press. The steam pipes I², I² lie within the channel C. 90 The casing I is provided with perforations J which are provided with swinging coverings J¹ normally in the closed position and held closed by means of the thumb nuts J². The rods G are perforated at a plurality 95 of points as at G¹, G¹.

K is a rod which may be inserted in the perforations J and as shown in Figure 4 may lie back of the platen E, and against which pressure may be exerted when it is 100 desired to press in the position shown in Figure 4.

Hinged on the bottom of the press casing are a plurality of perforated floor plates L.

These plates are hinged on the casing as at L¹ and are provided with swinging hooks L² by means of which they are held in place. In addition to these hooks, there are provided locking nuts L³ by means of which they may be rigidly locked against opening.

In the plates L are a plurality of perforations M which perforations are larger at their bottom than at the top as shown particularly in Figures 5 and 6. The top of the casing is provided with a plurality of swinging doors N. These doors are not perforated. They are locked in position by the locking nuts N¹ similar to the nuts L³ mentioned above. Along the side of the casing below the hinges N² of the doors N are mounted stop members N³ against which the members N rest when the top of the press is open as shown in Figure 5.

20 The lock nuts L³ are shown on an enlarged scale in Figure 10. As there shown they consist of a pivoted screw threaded shank L⁴ and the hand screw L⁵ mounted thereupon. The hand screw can be raised 25 to the dotted line position when the door is closed. The hook is then slipped into position, the screw is then rotated into the full line position and the member L³ is screwed down and the door is locked rigidly 30 into position.

As shown in Figure 9 a pin G² has been inserted in the perforation G¹ of one of the rods G.

Figure 7 is an enlarged elevation showing 35 the partition H. The partition proper is formed of a sheet of steel or other suitable metal O, upon which are fastened a plurality of half rounded members O¹ O¹. On the outside of each of these is secured a 40 perforated plate O². The partition members are provided with large lateral notches O³ adapted to engage the channel member C, and provided with small lateral notches O⁴ into which the chains H¹ may be dropped.

45 Although I have shown an operative device, still it will be evident that many changes in size, shape and arrangement of parts might be made without departing materially from the spirit of my invention; and I wish therefore that my showing be taken as in a sense diagrammatic.

In Figure 11, which is a view similar to Figure 9, is shown a modification of the device. Instead of using the solid rods G, 55 one or more hollow pipes P are used. These pipes are connected to the source of steam and are thus heated and serve to heat the interior of the press and to heat its contents. The pipes are provided with one or 60 more circumferential grooves P¹. They pass through the platen and partitions just as do the rods G. When it is desired to use them to draw the platen forward, they are secured to the platen by means of U-bolts Q, which slip over the lugs on the platen,

and whose shanks lie within the grooves P¹. For the purpose of convenience the U-bolts are provided with eyes Q¹ by means of which they may be handled or secured to the machine by a short chain so as to prevent 70 loss.

As shown in Figures 2, 3, and 4, at the right hand end of each figure, I have added the plates R. I have shown these plates inserted only between some of the partition plates, but in practice, if used at all, they would be inserted between all the partition plates. The plates are simply flat metallic plates. When the press is to be filled as shown in Figure 2, the plates rest in the 80 angular position shown. The press is then filled and material rests upon the plates and between the partitions. As the press is closed the bottom sides of the plates are pressed over laterally and the plates tend to 85 assume an upright position. Since there is practically no pressure on the under side of the plates, before the pressing operation is complete, they will assume a full upright position and will lay against the partitions 90 as shown in Figures 3 and 4. This shifting of the position of the plates R allows for some expansion downward of the cake and thus serves to a considerable degree as a safety valve to prevent damage to the press 95 from excess pressure.

When the press is opened after the cake has been removed, the plates are easily readjusted to the position shown in Figure 1.

The use and operation of my invention 100 are as follows:

The press is opened for pressing as shown in Figure 1. In that position the top plates will be open and the bottom plates closed. The material to be pressed will be run into 105 the press and the top plates then preferably closed. Pressure will then be exerted, the plunger expelled and the platen F, together with the partition H move into the position shown in Figure 3. This is the full extended position of the plunger. The pin G² will then be inserted in the rods G and pressure applied to the opposite side of the plunger. Thus the entire pressing assembly, including the platens E and F and the 110 partitions H with the material between them will be bodily moved into the position shown in Figure 4. Then the rod K will be put into one of the perforations J, being positioned back of the platen E. 115 Pressure will then again be exerted on the opposite side of the plunger and the material will be further compressed, the platen F, together with the partitions H and the material moving laterally against the platen 120 E which is now held by the rod K. This operation may be repeated a number of times until a sufficient pressing effect has resulted. By this means with a plunger having, for example, a movement of but thirty 125

inches will have a total pressing movement of several times that, so that one hundred and twenty inches may be effected. Thus with a small apparatus very great pressing effect may be carried out.

The platens and the partitions, as they move longitudinally across the floor plates L, serve to scrape or shear off the material on the bottom plates which may have entered the apertures M and which may project upwardly therefrom. The apertures being downwardly and outwardly flared, the shearing off of the material above the top of the bottom plates frees the material which might otherwise clog the apertures.

I claim:

1. In a press, a plurality of platens and a pressure cylinder for compressing them together, and means for moving said platens together throughout a distance greater than the effective length of said compression cylinder.

2. In a horizontal press, a plurality of platens and a pressure cylinder for compressing them together, and means for moving said platens together throughout a distance greater than the effective length of said compression cylinder.

3. In a press, a plurality of platens and a pressure cylinder, means for moving one of them toward the other and means for moving the platens so that said first mentioned platen may be moved in to compress a distance greater than the effective length of said compression cylinder.

4. In a horizontal hydraulic press, a plurality of platens and a pressure cylinder, means for moving one of them toward the other and means for moving the platens so that said first mentioned platen may be moved in to compress a distance greater than the effective length of said compression cylinder.

5. In a press, a plurality of platens, means for holding one against displacement, and means for moving another toward said platen, means for moving said platens in the reverse direction, means for supporting said first mentioned platen against displacement in the new position and means for again moving said second platen toward said first mentioned platen and means for further repeating this cycle of operations.

6. In a horizontal press, a plurality of platens, means for holding one against displacement, and means for moving another toward said platen, means for moving said platens in the reverse direction, means for supporting said first mentioned platen against displacement in the new position and means for again moving said second platen toward said first mentioned platen and means for further repeating this cycle of operations.

7. In a press, a plurality of platens and

a pressure cylinder for compressing them together, and means for moving said platens together throughout a distance greater than the effective length of said compression cylinder, and between said platens a plurality of partitions, and means for automatically spacing said partitions when the press is in the extended position.

8. In a press, a plurality of platens and a pressure cylinder, means for moving one of them toward the other and means for moving the platens so that said first mentioned platen may be moved in to compress a distance greater than the effective length of said compression cylinder, and between said platens a plurality of partitions, and means for automatically spacing said partitions when the press is in the extended position.

9. In a horizontal hydraulic press a pair of platens, means for supporting one of them and for moving the other toward it, means for moving both platens in the reverse direction, additional means for supporting said first mentioned platen and means for moving said second platen again toward the first platen and for further repeating this cycle of operations, and between said platens a plurality of partitions and means for automatically spacing said partitions when the press is in the extended position.

10. In a press, a plurality of platens and a pressure cylinder for compressing them together, and means for moving said platens together throughout a distance greater than the effective length of said compression cylinder, and means for heating said press.

11. In a press, a plurality of platens and a pressure cylinder for compressing them together, and means for moving said platens together throughout a distance greater than the effective length of said compression cylinder, and an enclosure for said press surrounding the same and closed at its ends only by said platens.

12. In a press, a plurality of platens and a pressure cylinder, means for moving one of them toward the other and means for moving the platens so that said first mentioned platen may be moved in to compress a distance greater than the effective length of said compression cylinder, and an enclosure for said press surrounding the same and closed at its ends only by said platens, said enclosure provided with movable top and bottom covers for the admission to and removal from the press of material to be pressed.

13. In a press, a plurality of platens and a pressure cylinder, means for moving one of them toward the other and means for moving the platens so that said first mentioned platen may be moved in to compress a distance greater than the effective length of said compression cylinder, and an en

- closure for said press surrounding the same and closed at its ends only by said platens, said enclosure provided with movable top and bottom covers for the admission to and 19. In a press a plurality of platens and partitions between said platens, and heating means within said press, said partitions being mounted thereupon.
- removal from the press of material to be 5. In a press in combination with an aper- pressed, and the bottom of said enclosure tured bottom therefor, members slidably provided with perforations for draining, mounted within said press adapted to said perforations expanding in width down- contact said bottom and to slide across the ap- wardly. 6. In a hydraulic press a partition, said 70 tures in said bottom in such manner as to presser formed of a main sheet-like mem- scrape and shear off material lodging within ber provided with reinforcing and spacing the apertures and projecting upward into ribs and having perforated exterior walls on the press.
- either side carried by said ribs. 7. In a hydraulic press, a partition, said 75 partition formed of a main sheet-like mem- ber provided with reinforcing and spacing ribs and having perforated exterior walls on either side carried by said ribs, said ribs 20 stopping short of the lower edge of said partition.
8. In a hydraulic press, a partition, said 80 partition formed of a main sheet-like mem- ber provided with reinforcing and spacing ribs and having perforated exterior walls on either side carried by said ribs, said ribs 25 stopping short of the lower edge of said partition.
9. In a press, a plurality of platens, and 85 a pressure cylinder for compressing them together, and means for moving said platens 10. In a press, a pair of platens, one of together throughout a distance greater than said platens adapted to be held against the effective length of said compression cylinder, and means for heating the exterior and interior of said press, comprising a heating means within said press.
11. In a press, a pair of platens, one of 90 said platens adapted to be held against movement, the other adapted to be moved toward said platen and carrying a draw bar fixed to said second platen and extending through said first platen, means for attaching said first mentioned platen to said bars so that it may be withdrawn in response to movement of said second mentioned platen in the reverse direction.
12. In a hydraulic press, a horizontal hy- 95 40draulic cylinder, a pair of movable platens, one of them directly connected to the plunger in said cylinder, a pair of connecting rods fixed to said platen and passing through said second platen, partitions between said platens mounted on said rods, an enclosure for said assembly closed at its ends only by said platens and provided with removable top and bottom covers, said first platen 13. In a press, a partition and means for 100 heating it, said partition being movable with relation to said heating means, said heating means adapted to serve as a support for said partition.
14. In a press, a partition and means for 105 conducting heat thereto, said partition being movable with relation to said heat conducting means, said heat conducting means adapted to serve as a support for said partition.
15. In a press, a partition and a heating 110 pipe, said partition mounted upon said heating pipe and adapted freely to move with relation thereto and to be heated therefrom in whatever position it may occupy.
16. In a press, a plurality of platens, a 115 pressure applying means for compressing them together, and means for moving said platens together throughout a distance greater than the effective operating travel of said pressure applying means.
- Signed at Chicago, county of Cook and State of Illinois, this 8th day of November, 1923.

JOHN J. BERRIGAN.
